UNITED STATES PATENT OFFICE.

MARINUS W. WARNE, OF ST. LOUIS, MISSOURI.

IMPROVED SODA-WATER FOUNTAIN.

Specification forming part of Letters Patent No. 39,976, dated September 15, 1863.

To all whom it may concern:

Be it known that I, MARINUS W. WARNE, of the city and county of St. Louis, and State of Missouri, have invented a new and Improved Soda Water Fountain; and I do hereby declare that the following is a full, clear, and exact description of the same, reference being had to the accompanying drawings, forming part of this specification, in which—

Figure 1 is a vertical section of the fountain. Fig. 2 is a plan of the same, with the cover removed to show the interior arrangement.

Similar letters of reference indicate corresponding parts in both figures.

This invention is of that kind from which a solution of supercarbonate of soda and a mixture of sirup and acid are drawn separately into the glasses.

The invention consists in a novel arrangement of an air-chamber, in combination with the tank which contains the soda solution, and with a suction and force pump and elevated draft-tube, whereby a quantity of the solution is retained in the vessel under sufficient pressure to force it through the draft-tube, and is kept cool for delivery to the said to be.

To enable others skilled in the art to make and use my invention, I will proceed to describe its construction and operation.

A is an upright box or stand, of suitable height to form a counter, and of suitable size to contain the large tank B, in which the solution of supercarbonate of soda is made and kept, and a number of smaller compartments, *a a*, for the reception of the sirups containing the necessary acid to produce effervescence, such sirups either being placed directly into the said compartments or in bottles arranged therein, and being drawn off in the usual or any suitable manner.

C is a hinged lid, forming part of the top of the stand, and, when open, uncovering the sirup-compartments *a a* and a portion of the soda-tank B, and permitting them to be filled.

H is a flap, hinged to the upper part of the front of the stand A, and capable of being raised up to the position shown in red outline in Fig. 1, to form an extension of the counter, or folded down against the front of the stand, as shown in black outline in the same figure, to be out of the way.

D is the suction and force pump, arranged outside and attached to the back of the stand

A, and operated by a hand-lever, E. The suction pipe *b* of this pump is connected with the bottom of the soda tank B, and the force-pipe *c* leads through the bottom of said tank into the bottom of the air-vessel F, which is arranged within the said tank. The draft-tube G, of siphon form, is fitted and secured in the top of the air-chamber, and passes through the top of the stand. The lower part of the said tube extends a short distance down into the air-chamber, in order that some air may always be retained in the upper part of said chamber; and above the stand A there is provided in the said tube a cock, *d* which is opened to draw off the soda solution.

The ice for cooling the soda-water is placed directly into the tank B, around the air-chamber F.

To set the fountain in operation, the supercarbonate of soda, water, and ice are put in the tank B, and the sirups and acid into the compartments *a a*; and a few strokes are given to the pump to draw and force the soda solution from the tank B into the air chamber and compress a quantity of air in the upper part of the said chamber around the lower part of the draft tube. When a glass of soda-water is called for, a suitable quantity of sirup is first drawn into the glass, which is afterward placed under the tube G and filled up with the soda solution by opening the cock *d*, said solution being forced up through the tube by the pressure of the air in the upper part of the chamber F, and that which is drawn being always cool, as the air-chamber, from which it comes directly, is surrounded by ice. A few strokes of the pump will be necessary from time to time to replenish the air-vessel with the solution and recompress the air therein; but if the chamber is of suitable capacity a great many glasses may be drawn without any pumping being necessary.

What I claim as my invention, and desire to secure by Letters Patent, is—

The arrangement of the air-chamber F within the soda-tank B, and in combination with the suction and force pump and the draft-pipe, the whole arranged relatively to the stand C substantially as and for the purpose herein described.

M. W. WARNE.
